DESIGN FOR A DISPLAY STAND FOR A VACUUM CLEANER OR SIMILAR ARTICLE

Arthur L. McCarthy, Detroit, Mich., assignor to Eureka Vacuum Cleaner Company, Detroit, Mich., a corporation of Michigan

Application September 26, 1938, Serial No. 80,109

Term of patent 14 years

To all whom it may concern:

Be it known that I, Arthur L. McCarthy, a citizen of the United States of America, residing at Detroit, in the county of Wayne and State of Michigan, have invented a new, original, and ornamental Design for a Display Stand for a Vacuum Cleaner or Similar Article, of which the following is a specification, reference being had therein to the accompanying drawing, forming a part thereof, wherein the figure illustrates a perspective view of a display stand for a vacuum cleaner or similar article embodying the new design.

I claim:

The ornamental design for a display stand for a vacuum cleaner or similar article, substantially as shown.

ARTHUR L. McCARTHY.
